GRASS CUTTER EMPLOYING RAZOR BLADES

Cornelius A. Hubner, Bloomingdale, N. J.

Application November 2, 1945, Serial No. 626,271

2 Claims. (Cl. 30—299)

1

The invention here disclosed relates to devices for cutting grass and weeds, and the general objects of the invention are to provide practical and desirable means for edging and trimming lawns and the like.

Specifically it is the purpose of the invention to provide a cutter which will operate with a short movement, as distinguished from the swinging action of an ordinary sickle or the like and which will be light in weight and small in size so that it may be used in restricted places and close against obstructions, such as building walls, trees and other fixed objects.

Additionally it is a purpose of the invention to provide a cutter of the distinguishing characteristics mentioned which, as it becomes dulled with use, may have its cutting edge or edges easily and quickly renewed and which will be of such design that renewal of the cutting edges may be accomplished without danger to the user.

Other desirable objects and the novel features by which the purposes of the invention are attained are set forth or will appear in the course of the following specification.

The drawing accompanying and forming part of the specification illustrates certain present preferred embodiments of the invention. Structure, however, may be modified and changed as regards the present illustration, all within the true intent and broad scope of the invention as hereinafter defined and claimed.

Fig. 1 in the drawing is a perspective view illustrating a simple form of the cutter using single edged razor blades for the cutting edge;

Fig. 2 is a broken, part sectional plan view of the handle end portion of the cutter;

Fig. 3 is a broken cross sectional view as on substantially the plane of line 3—3 of Fig. 2;

Fig. 4 is a similar view of a double edged form of the invention, made to cut both ways;

Fig. 5 is a broken sectional detail of a form of the cutter made to use double edged razor blades;

Fig. 6 is an edge view of a double edged blade and a hinged form of clamp for securing the same in the holder illustrated in Fig. 5;

Fig. 7 is a broken, part sectional plan view of this modified form of the cutter; and

Fig. 8 is a broken, perspective view of a modified form of blade clamp for use in the holder.

As will be clear from the several views, the invention involves the utilization of razor blades to provide a keen, sharp cutting edge and the provision of means for holding these blades firmly but readily removable in proper cutting relation.

In a preferred form the holder consists of a single piece of spring sheet metal folded upon

2

itself in two steps or stages, a base portion made up of a rounded back 10 and closely spaced parallel sides 11 and a clamping portion made up of more closely spaced, substantially parallel jaw forming strips 12 connected with the back strips 11 by the abruptly indented shoulders 13.

In rolling the sheet or strip material to the form described, the parallel side portions are tensioned toward each other in convergent relation so as to firmly grip razor blades which have been slid into position between them.

Figs. 1 and 3 show how the spacing of the relatively stepped portions 11 and 12 is such as to accommodate reinforced back portions 14 of the blades between the more widely spaced parts 11 and the cutting blade portions 15 between the more closely spaced lip or jaw parts 12.

In final assembly the blades will be held approximately as shown in Fig. 3 with the flat parallel edge or jaw portions 12 firmly gripping the sides of the blades back of the cutting edge and the reinforced back portion freely received in the flat chamber formed by the spaced parallel side portions 11, in back of the inwardly contracted shoulders 13. In this manner the gripping force is applied directly to the blades, close up to the actual cutting edge, and the reinforced backs of the blades simply serve as abutments engaging the rounded wall 10 at the back to limit inward movement of the blades in the holder and engaging the shoulders 13 at the front to prevent or limit outward slipping movement of the blades.

The blade holder is provided with a suitable handle. In the illustration the rounded back 10 is continued at one end and the edges rolled together at 16 to form a substantially cylindrical tubular extension. This in itself may be shaped as a handle but usually it may be preferred to insert a wire or rod extension 17 in the tubular portion, the latter being offset and carrying a suitable handle grip 18.

The shape, length, extent of offset and other features of the handle structure may be varied to suit different requirements, that illustrated being shown as a typical or more or less usual example of handle structure.

Also, if desired, the handle grip portion may be made readily removable from the tubular handle extension of the blade holder to enable ready substitution of different kinds of handles with the same blade holder.

Fig. 4 shows how the device may be made up as a double edged cutter by simply securing a duplicate flat spring blade holder to the back of the first blade holder, as by means of a sol-

dered, welded or other suitable connection such as indicated at 19.

Figs. 5, 6 and 7 show how the blade holder may be made to take double edged blades 20, by providing a blade clamping insert which can be loaded and then slipped into position between the parallel side portions of the holder. In these views the same reference characters are employed since the holder structure is essentially the same, but it will be appreciated that actually the holder may be made with the parallel side portions formed slightly wider apart to take the blade holder insert, and possibly of less extent in width to leave the cutting edge portion of the blade sufficiently exposed.

The blade holding insert shown in Figs. 5, 6 and 7 consists of a pair of hinge leaves 21 shaped to the flat, stepped contour of the spring holder and hingedly connected together at the back at 22. This insert is made of a length approximating that of the holder and is used by first laying the blades end to end in the opened clamp, Fig. 6, and then inserting the clamp thus filled, endwise into the outer open end of the spring holder.

Fig. 8 illustrates a modified form of insertable clamp structure embodying a U-bent sheet metal backing 23 having relatively wide and narrow side portions 24, 25, adapted to readily receive the flat double edged blades 20, and an insertable clamp strip 26 to overlie the blades and confined by the narrower jaw portion 25. When the blades are made up into this sub-assembly, as illustrated in this view, the whole may then be slipped into the parallel sided spring holder.

The cutter constructed as disclosed is light but strong and the blades are firmly held with their cutting edges coextensive in substantial alignment and properly braced so as to act as efficient cutters.

The overall width of the device need only be slightly greater than the width of the blades, so the cutter as a whole constitutes only a relatively narrow assembly which can be reached into small places, as for cutting grass and weeds which otherwise would be practically inaccessible.

The lightness of the implement facilitates and encourages use of the tool with a drawing or shaving type of cut, as distinguished from the long, swinging cut usually required with a sickle type of tool. This possibility of cutting with a draw stroke and with a short movement is a further feature in enabling use of the implement in restricted spaces.

The companion lips or jaws 12, being continuous and flat in extent, reinforce and prevent bending of thin razor blades. With this structure also the blades are so firmly held that they cannot accidentally slip out of place. On the other hand, it is a relatively simple matter to remove blades, as by engaging the innermost blade over the edge of a curb or other stationary object and pulling endwise on the handle. Conversely, fresh blades can be easily inserted by entering them one after another in the open, outer end of the holder and pushing them against some stationary objects.

These are simple operations through which the blades may be easily removed and inserted. Because of the effectiveness of the tool, old or used razor blades may be employed as well as new blades. The edges of the blade clamping jaws are shown as straight and continuous. If desired, though, these edges may be serrated, the points provided by such serrations acting as fingers to

grip the blades. To prevent the tool accidentally digging into the ground, a ground engaging shoe or guard may be provided on the under side of the holder.

5 What is claimed is:

1. A grass cutting implement comprising an elongated integral one-piece holder of spring sheet material folded longitudinally on itself and having a rounded back portion with spaced sides projecting therefrom in substantially parallel relation, sharply indented shoulders at the outer edges of said spaced sides and closely approached continuous flat and unobstructed blade gripping jaws projecting from the inner portions of said 10 indented shoulders, a plurality of razor blades in end-to-end abutting engagement in said holder, said blades having thickened back portions, said sides being spaced widely enough apart to receive the thickened back portions of said 15 blades, said blades being disposed between said jaws and said indented shoulders being spaced from the rounded back a distance slightly greater than the width of the thickened back portions of the blades to thereby confine said back portions against lateral movement in opposite directions to hold the blades against outward or inward movement in said jaws and said spaced sides and blade gripping jaws being open at one end of the holder to admit entry of the blades 20 there-between and the longitudinal sliding of successive blades into final position in the holder.

2. A grass cutting implement comprising an elongated integral one-piece holder of spring sheet material folded longitudinally on itself and 25 having a rounded back portion with spaced sides projecting therefrom in substantially parallel relation, sharply indented shoulders at the outer edges of said spaced sides and closely approached continuous flat and unobstructed blade gripping 30 jaws projecting from the inner portions of said indented shoulders, a plurality of razor blades in end-to-end abutting engagement in said holder, said blades having thickened back portions, said sides being spaced widely enough apart to receive the thickened back portions of said 35 blades, said blades being disposed between said jaws and said indented shoulders being spaced from the rounded back a distance slightly greater than the width of the thickened back portions of the blades to thereby confine said back portions against lateral movement in opposite directions to hold the blades against outward or inward movement in said jaws and said spaced sides and blade gripping jaws being open at one end of the holder to admit entry of the blades 40 there-between and the longitudinal sliding of successive blades into final position in the holder.
